UNITED STATES PATENT OFFICE.

FRIEDERICH MÜLLER, OF HARTFORD, CONNECTICUT, ASSIGNOR TO PRATT & WHITNEY COMPANY, OF NEW YORK, N. Y., A CORPORATION OF NEW JERSEY.

AUTOMATIC GRINDING-MACHINE.

1,287,731.

Specification of Letters Patent. Patented Dec. 17, 1918.

Application filed May 2, 1917. Serial No. 165,903.

To all whom it may concern:

Be it known that I, FRIEDERICH MÜLLER, a citizen of the United States, residing at Hartford, in the county of Hartford and State of Connecticut, have invented certain new and useful Improvements in Automatic Grinding-Machines, of which the following is a specification.

The invention is particularly adapted for use with or as a part of a grinding machine of the type disclosed in my reissued Patent No. 13,930, dated June 15th, 1915. A machine of this type is provided with a broad-faced wheel which has a width at least as great as the length of the articles being ground, thus enabling the machine to effect grinding from end to end of the article at one time. Such a machine is adapted for grinding twist drills, reamers, mandrels, cylindrical or tapered pins and many other articles. In this specification, for the sake of convenience, I will refer to the grinding of "tools," but it will be understood that the term is used in a broad generic sense and is intended not only to include drills, reamers, etc., but also mandrels, tapered pins and other articles adapted to be ground.

As disclosed in the said reissued Patent No. 13,930 the grinding machine was constructed to stop automatically after the completion of one grinding operation, and it was then necessary for the operator to manually remove the tool or other article that had been ground and put a new one in place on the centers. After that it was necessary for the operator to start the operation of the machine. In accordance with the present invention the entire operation is completely automatic, means being provided whereby the tools or other articles to be ground are automatically supplied and removed without interrupting the operation of the machine. It is only necessary for the operator to supply blanks from time to time to a magazine which is provided.

The principal object, therefore, of the present invention is to provide a grinding machine having automatic means for supplying and removing the tools or other articles to be ground. Other objects of the invention will be apparent from the following specification and claims.

In the accompanying drawings I have shown a grinding machine embodying my invention, this being in many respects similar to that shown in my aforesaid reissued Patent No. 13,930. It will be understood that the drawings are intended to be merely illustrative of the invention and are not to be construed as defining or limiting its scope. Many changes in details and in general arrangements of parts can be made without departing from the scope of the invention as set forth in the accompanying claims.

Of the drawings:

Fig. 1 is a front elevation, the several parts being shown in the positions which they occupy when a fresh blank is being supplied for grinding.

Fig. 2 is a side elevation taken from the right.

Fig. 3 is a plan view, the belt tighteners and other parts being omitted.

Fig. 4 is a transverse vertical sectional view taken along the line 4—4 of Fig. 1.

Fig. 5 is a plan view of the wheel feed slide.

Fig. 6 is a fragmentary longitudinal sectional view taken along the line 6—6 of Fig. 5 and showing the wheel feed slide and other parts immediately associated therewith.

Fig. 7 is a horizontal sectional view taken along the line 7—7 of Fig. 2.

Fig. 8 is a view showing a development of one of the cams.

Fig. 9 is a fragmentary vertical sectional view showing the change-speed drive gearing.

Fig. 10 is a fragmentary vertical sectional view showing the change-speed gearing and associated parts, this view being taken along the line 10—10 of Fig. 9.

Fig. 11 is a fragmentary horizontal sectional view on an enlarged scale showing the grinding wheel and parts of the tool supporting mechanism. In this view the wheel is shown in operative engagement with the work, and the magazine mechanism and other parts are omitted for the sake of clearness.

Fig. 12 is a front elevation with parts in section, showing the same mechanism which is shown in Fig. 11.

Fig. 13 is a plan view showing the table

and slide for carrying the headstock and tailstock. In this view the table is angularly adjusted with respect to the slide.

Fig. 14 is a detail view showing a part of 5 the magazine mechanism.

Fig. 15 is a view similar to Fig. 14 but showing the elements of the mechanism in another position.

Fig. 16 is a view showing a development 10 of one of the cams.

Referring to the drawings, 1 represents the main frame or base of the machine, this being adapted to rest upon and be secured to the floor. The grinding wheel is indicated at 2, this wheel preferably being provided with a relatively broad face and being formed in several sections as indicated. The wheel is carried by the base 1, being mounted upon a horizontal shaft 3 which is rotatable 20 in bearings 4, 4.

Suitable devices are provided for holding and rotating a tool to be ground, in cooperative relationship with the wheel. These devices will be described in detail herein- 25 after, and for the present it is sufficient to state that they comprise centers 5 and 6 adapted to engage the respective ends of the tools.

The grinding wheel may be driven in any 30 of several ways, but, as illustrated, the wheel is driven by means of a belt 7 passing over a belt wheel 8 connected with the grinding wheel and over a belt wheel 9 mounted on a rotatable shaft 10. A suitable tightener 7^a 35 cooperates with the belt 7. Carried by the main frame in suitable bearings is a drive shaft 11 provided with a driving means such as a belt wheel 12. The shaft 10 is driven from the main shaft 11 by means of a belt 40 13 which passes over a belt wheel 14 on the shaft 10 and a belt wheel 15 on the shaft 11. A spring controlled tightener pulley 16 is provided for the belt 13.

The wheel 2 with its shaft and the bearings, is mounted upon the main base 1 through intermediate parts which permit the wheel to be moved horizontally in several ways for the purpose of adjustment and for the purpose of feeding. As shown most 45 clearly in Figs. 2 and 4, the bearings 4, 4 are secured to or formed on a slide 17 which is adjustable in the direction of the wheel axis on suitable guides formed on a plate 18. This slide 17 also carries the bearings for 50 the shaft 10. By moving the slide 17 with respect to the plate 18 the wheel can be preliminarily moved longitudinally into an operative position which is suitable for the work to be done. By means of screws 19 55 and a gib 20 the slide 17 can be locked in adjusted position. Secured to the slide 17 is a suitable cover or casing 21 partly inclosing the wheel.

The plate 18 constitutes a slide adjustable

at right angles to the axis of the wheel 6 along suitable ways formed on a carriage 22. A rotatable rod 23 coöperating with a micrometer head 24 serves as the means for adjusting the slide 18 on the carriage 22. By this means the wheel can be adjusted toward 70 or away from the work to vary or control the diameter of the finished tools.

The carriage 22 is mounted in suitable ways formed on the base 1, these ways being at right angles to the axis of the driving 75 wheel and parallel to the ways along which the slide 18 is adjustable. Also mounted in suitable ways in the base 1 is a feed slide 25 mounted to move along lines parallel to the axis of the grinding wheel and at right 80 angles to the lines of travel of the carriage 22. This slide 25 with associated parts is shown in detail in Figs. 5 and 6. Referring to these figures it will be observed that there is mounted upon the slide a cam plate 26 85 pivoted at 27 and adjustable about the pivot by means of a bar 28 controllable by a screw 29. Also secured to the slide 25 are two co-operating cam plates 30 and 31. Depending from the carriage 22 is a roller 32 which is 90 adapted to be engaged by the said cam plates 26, 30 and 31.

Positioned immediately beneath the slide 25 is a rotatable cam drum 33 which is mounted on a shaft 34 supported in suitable bearings in the main base frame. This cam drum 95 is provided with cam plates 35, 36, 37, 38 and 39 which are shown in development in Fig. 8. Depending from the slide 25 is a roller 40 adapted to be engaged by the said 100 cam plates 35 to 39. The cam drum 33 is rotated in the direction indicated by the arrow by means of mechanism which will presently be described.

Assuming the slide 25 to be at the extreme right-hand position as viewed in Fig. 6, the roller 40 would be in the relative position indicated by full lines in Fig. 8. At the same time the roller 32 would occupy the relative position shown in Figs. 5 and 6, the carriage 22 being at its extreme rearward position with the grinding wheel withdrawn from engagement with the work. The movement of the drum causes the cam plate 35 to force the roller 40 and the slide 25 quickly 115 toward the left. This quick movement of the slide 25 toward the left causes the roller 32 to be forced along the surface of the cam plate 30, thus quickly moving the carriage 22 and moving the wheel into engagement 120 with the work. As soon as the roller 40 is disengaged by the cam plate 35 it is engaged by the cam plate 36 which is less sharply inclined and which serves to move the roller and the slide 25 slowly toward the left. During this slow movement of the slide toward the left the roller 32 is in engagement with the cam plate 26 which is inclined to a 125

greater or less extent in accordance with the adjustment of the bar 28. The inclined surface of the plate 26 causes the roller 32 and the carriage 22 to be moved very slowly forward, thus feeding the grinding wheel to its work. At the end of the cam plate 38 is a plate 39 which is perpendicular to the axis of rotation. While this plate 39 is passing the roller no movement of the slide 25 takes place and therefore no movement of the carriage 22 takes place. The wheel therefore is held in its most advanced position, the rotation of the tool in the meantime being continued, thus serving to effect 15 a supplemental grinding to remove any unevenness and to compensate for any spring in the tool or in its supports. Preferably an adjustable screw 41 is provided for accurately limiting the forward movement of the carriage 22.

When the cam plates 38 and 39 engage the roller 40, the roller and the slide 25 are moved quickly toward the right. This movement brings the cam plate 31 into engagement with the roller 32, thus forcing the carriage 22 and the grinding wheel quickly backward and out of operative position. After being disengaged by the cam plate 39 the roller 40 is again engaged by the cam plate 35 and the operation before described is repeated.

Means are provided for driving the cam shaft 34 from the main drive shaft 11. Mounted on the shaft 11 is a spiral gear 42 which meshes with a similar spiral gear mounted on a short horizontal shaft 43 positioned below the shaft 11 and extending at right angles thereto. Mounted in alignment with the shaft 43 is a shaft 44 carrying a worm 45 which meshes with a worm wheel 46 mounted on the cam shaft 34. A collar 47 is splined on the shaft 44 and is provided with teeth adapted to mesh with similar teeth on a collar 48 secured to the shaft 43. It will be seen that when the teeth of the collars 47 and 48 are in engagement, power will be transmitted from the shaft 43 to the shaft 44, the cam shaft 34 with the drum 33 thereon being rotated.

In order that the speed movement of the shaft 34 and the associated parts may be changed, a differently speeded mechanism is also provided for rotating the shaft 44. Mounted at the right hand end of the main drive shaft 11 is a set of cone pulleys 49. Mounted upon a short shaft 50 is a companion set of cone pulleys 51. A belt 52 connects the two sets of pulleys and is movable from one pair of pulleys to another to change the relative speeds of the two shafts 11 and 50. Mounted on the shaft 50 is a spiral gear 53 which meshes with a spiral gear 54 which is rotatable on the shaft 44. The aforesaid collar 47 is provided with

teeth on its left-hand end which are adapted 65 to engage similar teeth on the gear 54. When the collar 47 is moved toward the left it is disengaged from the collar 48 and is connected with the gear 54. The gear 54 has a speed of rotation which is considerably 70 slower than that of the shaft 43 and the collar 48, and therefore when the collar 47 is in its left-hand position the shaft 44 is driven relatively slowly. It will be understood that the speed of the shaft when driven 75 in this way can be changed by moving the belt 52. When the collar 47 is in its central position no power is transmitted and the shaft 44 and all parts driven thereby are 80 idle.

The collar 47 is provided with an annular groove into which project pins carried by an oscillatory lever 55. This lever is mounted at the lower end of a rock shaft 56 and at the upper end of the shaft there is mounted 85 a lever 57 carrying a roller 58. Pivotedly mounted at a point opposite the rock shaft 56 is a bell-crank lever 59 in one arm of which there is carried a spring-pressed plunger 60. The forward end of the plunger 90 is V-shaped and is adapted to engage and coöperate with the roller 58 on the lever 57. The other arm of the bell-crank lever 59 is provided with a roller 61.

Mounted upon the end of the shaft 34 is 95 a shipper wheel 62 and adjustably secured to this wheel 62 are two oppositely shaped shipper dogs 63 and 64 each adapted to engage the roller 61 and thus move the bell-crank lever 59 first in one direction and then in 100 the other. When the lever 59 is moved in the counter-clockwise direction from the position shown in Figs. 3 and 7, the plunger 60 engages the roller 58, thus, by means of the lever 57, the rock shaft 56 and the lever 105 55, serving to move the collar 47 into engagement with the gear wheel 54 on the shaft 44. When the lever 57 reaches its limit of movement the plunger 60 is forced inward by the roller 58 and the plunger 110 passes the roller and takes a position on the front side thereof. The shaft 44 and the connected parts are then driven from the gear wheel 54 and continue to be so driven until the next shipper dog engages the roller 115 61 to move the bell-crank lever in the clockwise direction. Then the plunger 60, acting through the roller 58 and associated parts, serves to move the collar 47 into engagement with the collar 48, the shaft 44 120 and connected parts being then driven at increased speed through the cone pulleys and other parts that have been described. When the lever 57 reaches its limit of movement the plunger 60 is again forced inward and 125 moves past the roller 58 taking a position on the rear side thereof, as shown. In this way the shaft 44 is automatically connected

alternately to be driven relatively slowly from the gear wheel 54 and relatively rapidly from the shaft 43. The shipper dogs 63 and 64 are so positioned on the wheel 62 that the more rapid movement begins approximately when the roller 40 is engaged by the cam plate 38, and the less rapid movement begins when the roller 40 is engaged by the cam plate 36. In this way the necessarily slow movements of the machine during grinding are secured, and then the movements of the machine are accelerated during the time that a finished tool is being removed and a fresh blank put in place.

15 Preferably, in order that the operator may readily stop the machine when desired, the lever 57 has connected with it a link 65 which extends forward to the front part of the machine. Pivotedly connected with the 20 forward end of the link is a handle 66 which is movable at right angles to the axis of the link. Associated with the handle 66 is a cam plate 67 having a V-shaped notch therein. During normal operation of the machine the handle 66 is in its left-hand position as shown in Fig. 1, and the link and the handle are free to move forward and backward as the lever 57 is oscillated. When the operator desires to stop the machine he swings the handle 66 toward the right, thus forcing it into engagement with the beveled edges of the notch in the cam plate 67. The handle is finally forced into the bottom of the notch, thus assuming a 30 central position and causing the lever 57 to assume a central position. In this way the collar 47 is moved to and is held in a central neutral position out of engagement with the shaft 43 and the gear wheel 54. Thus 40 the shaft 44 and all parts connected therewith are stopped.

As has already been stated, the tools to be ground are supported by centers 5 and 6. These centers are carried respectively by a 45 headstock 68 and a tailstock 69 which are carried by a main supporting slide 70 which rests upon longitudinal ways formed on the main frame 1. In order to insure smooth and even grinding, particularly when the 50 grinding wheel is formed in sections as shown, I provide means for effecting a relative longitudinal vibratory movement between the tool and the wheel during the grinding operation. This vibratory movement is brought about by causing the slide 70 to reciprocate relatively rapidly on its bed, carrying with it the headstock and tailstock and the tool being ground. The reciprocation is effected by means of a lever 71 which is pivoted to the main frame at 72. At 73 the lever 71 has a pivoted connection with the slide 70, there being sufficient lost motion at 73 to allow for the oscillatory movement of the lever. The lever 71 carries at 74 a roller which is engaged by cam

plates 75, 75 and 76, 76 carried by the cam drum 33. As shown in Fig. 8 the drum is provided with a large number of these plates so that during each grinding operation the lever is oscillated a large number of times. At a point opposite to the initial end of the cam plate 35, the series of plates 75-76 is interrupted and there are provided two parallel plates 77 and 78 which hold the roller 74 against movement while the roller 40 is being moved by the cam plates 38, 39 and 35. In this way the vibratory movement of the tool supporting parts is interrupted between grinding operations, that is while the finished tool is being removed and while a fresh blank is being put in place. When the normal grinding operation on the next tool is commenced the vibratory movement is resumed.

Preferably, in order that the machine may be used for grinding tapered tools or other articles as well as cylindrical ones, the headstock 68 and the tailstock 69 are mounted on the slide 70 indirectly by means of an intermediate table 79. This table 79 is provided with a longitudinal T-slot 80 by means of which the headstock and the tailstock and other parts can be secured in place. The table 79 is pivotally connected at 81 to the slide 70. By means of screws 82 and 83 the table can be moved about the pivot 81 and by means of screws 84 and 85 it can be locked in adjusted position. In this way the line of centers can be adjusted with respect to the face of the wheel, thus adapting the machine for grinding tapered tools or other articles.

In adjusting the machine for the grinding of tools of a given sort, the headstock and tailstock are positioned on the table 79 so as to properly locate the centers 5 and 6 with respect to the grinding wheel, the grinding wheel itself being moved longitudinally if necessary. The headstock is clamped in place by means of bolts 86, 86 which enter the T-slot 80, and the tailstock is clamped in place by means of bolts 87, 87 which enter the T-slot 80.

The center 5 of the headstock is carried by a live spindle 88 which is rotatable in bearings in the headstock. This spindle carries a belt wheel 89 which is engaged by a suitable belt, not shown. This belt preferably passes over a drive pulley which is quite wide, thus permitting the headstock to be adjusted longitudinally of the table without interfering with the operation of the belt. The drive pulley may conveniently be driven from the cone pulleys 90 carried by the main drive shaft 11.

Carried by the live spindle 88 is a suitable chuck 91 for engaging the blank and turning it. The form of the chuck will vary with the form of the blank, and in the drawings I have shown a chuck provided with a

pivoted finger 92, the end of which is bifurcated and is adapted to engage the tang at the end of the shank of a drill.

Means are provided for automatically adjusting the chuck into and out of engagement with the work in synchronism with the movement of the grinding wheel toward and away from the blank. Splined upon the spindle 88 is a grooved collar 93 which is adapted to engage an inclined surface on an arm formed integrally with the finger 92. When the collar 93 is moved toward the right the finger is swung toward the left out of engagement with the work. When the collar is moved toward the left the finger is released. Preferably there is provided a spring 94 for moving the finger toward the right into engagement with the work. For moving the collar 93 there is provided a forked lever 95 pivoted at 96 to the headstock casting and provided at 97 with pins entering the groove of the collar. Pivoted to the headstock casting at 98 is a bell-crank lever 99. One arm of this lever is connected with the forked lever 95 by means of an adjustable link 100. A coil spring 101 surrounds the link 100 and abuts against the headstock casting, normally tending to swing the lever 95 toward the right, thus moving the collar 93 toward the right and causing the opening of the chuck. Slidably in a bearing 102 formed on the headstock casting and in bearings 103 secured to the table 79, is a rod 104. This rod is provided at its left-hand end with an adjustable collar 105 having a beveled surface adapted to engage a boss 106 on the bell-crank lever 99. Adjustably secured to the rod 104 is a collar 107 carrying a pin which projects through a slot in the upper part of a lever 108. The collar 105 can be loosened to slide along the rod 104 when the headstock is moved. The lever 108 is mounted on a short rock shaft 109 which is carried in a bearing formed in a bracket 110 depending from the table 79. At the inner end of the shaft 109 is mounted a lever 111 carrying a roller 112.

For engaging the roller 112 to move it and for doing other work as will presently be described, there is provided a cam drum 113 mounted on a vertical shaft 114. This shaft is rotatable in suitable bearings in the main frame, there being a journal bearing 115 at the bottom and a cone guide bearing 116 at the top. The shaft 114 is driven by means of a worm 117 which is secured thereto and which meshes with a worm wheel 118 on a longitudinal horizontal shaft 119. The shaft 119 is driven from the aforesaid shaft 44 by means of bevel gears 120 and 121.

The drum 113 is provided with cam plates 122 and 123 adapted to engage and coöperate with the roller 112 on the lever 111. When the grinding wheel begins to move rearward to the position shown in Figs. 1, 2, 3 and 4,

the roller 112 is engaged by the cam plate 122 and is moved to its uppermost position. The lever 108 and the rod 104 are moved to their extreme left-hand positions, thus releasing the bell-crank 99 and permitting the lever 95 and the collar 93 to be moved toward the right by the spring 101. The movement of the collar toward the right swings the inward end of the finger 92 toward the left, thus withdrawing it from engagement with the tool.

The parts are held in the positions last described until a fresh blank is put in place on the centers and the grinding wheel is again moved into its forward position. Simultaneously with the forward movement of the grinding wheel the roller 112 is engaged by the cam plate 123 and is forced downward, thus moving the lever 108 and the rod 104 toward the right. The beveled surface of the collar 105 causes the bell-crank 99 to swing counter-clockwise, thus moving the lever 95 and the collar 93 toward the left. The finger 92 is then released and the spring 94 swings it toward the right into engagement with the tang on the shank of the blank.

The center 6 of the tailstock is carried by a spindle 124 which is slidably mounted in a sleeve 125 mounted in the tailstock casting. Projecting longitudinally from the rear end of the tailstock casting is a bearing or guide bar 126 upon which is slidably mounted a block 127. Projecting from the block 127 is an arm 128 provided with an aperture through which extends the rear end of the spindle 124. Positioned in this aperture is a friction block 129 adapted to be pressed against the spindle 124, a screw 130 being provided for this purpose. It will be seen that the block 129 serves as a means for frictionally connecting the spindle 124 with the block 127. Projecting from the block 127 at a point opposite to the arm 128 is a pin 131 which extends through a slot in the upper end of an elbow lever 132. This lever is pivoted at 133 to a bracket depending from the table 79. From the pivot point the lever 132 extends toward the left and is provided at its end with a roller 134 positioned in proximity to the cam drum 113. The cam drum is provided with cam plates 135 and 136 adapted to engage and coöperate with the roller 134.

Approximately simultaneously with the withdrawal of the grinding wheel from the work the roller 134 is engaged by the cam plate 135 and is moved upward. This upward movement of the roller causes the lever 132 to swing clockwise and to move the block 127 together with the spindle 124 and the center 6 toward the right. In this way the finished tool is released and is permitted to drop downward, it being remembered that at substantially the same instant the finger 92 has been moved toward the left to release the

tool at the headstock end. A little before the grinding wheel again reaches its forward position, the roller 134 is engaged by the cam plate 136 and is moved downward, thus 5 swinging the lever 132 in the counter-clockwise direction and moving the block 127 together with the spindle 124 and the center 6 toward the left. If in the meantime a fresh blank has been put in position in alinement 10 with the centers, either manually or by automatic mechanism such as will presently be described, the center 6 will engage the said blank and will push it toward the left until the center 5 also engages the blank. The 15 pressure of the center 6 against the blank is limited by the friction which is applied by the block 129.

As shown most clearly in Fig. 12, the 20 sleeve 125 is provided with upstanding ears 137 to which is horizontally pivoted a longitudinal lever 138. At the forward end of the lever is an adjustable screw 139 adapted to press against a friction block 140 which extends through an aperture in the sleeve 125 25 and engages the spindle 124. The rear end of the lever 138 is provided with a roller 141 which is adapted to be engaged by a cam surface 142 formed on the upper part of the arm 128.

20 When the block 127 with the arm 128 is moved forward it acts through the friction block 129 to move the spindle 124 and the center 6 forward into engagement with the blank in the way already described. The 30 several parts are so constructed and arranged that the extent of movement of the block 127 is considerably greater than that of the spindle 124. When the movement of the spindle is stopped by the engagement of 35 the center with the blank, the block 127 continues to move, thus causing the cam surface 142 to move under the roller 141 and swing the lever 138 in the counter-clockwise direction. The screw 139 presses against the 40 block 140, thus forcing the block into engagement with the spindle 124. In this way the spindle is securely locked against any 45 retrograde movement. When the block 127 is moved toward the rear the first result is to move the cam surface 142 relatively to the roller 141, thus releasing the roller and permitting the lever 138 to move and release 50 the friction block 140. As soon as the friction at the block 140 is removed the friction 55 at the block 129 serves to withdraw the spindle.

It frequently happens during grinding 60 that the blank becomes heated and expands to some extent, thus tending to cause undue pressure at the centers. To avoid this difficulty I preferably provide means whereby the tailstock center 6 is permitted to yield against a spring resistance to prevent any 65 excess pressure. As shown in Fig. 11, the sleeve 125 is movable longitudinally to a lim-

ited extent and is normally held in its forward position by means of a coil spring 143. Inasmuch as the sleeve is normally in its forward position, the spring 143 does not interfere in any way with the devices which have 70 been described for moving and locking the spindle 124. If after the spindle 124 is locked to the sleeve 125 as described, the spindle is forced toward the right by the expansion of the blank, the sleeve 125 and the several 75 parts carried thereby move with the spindle against the resistance of the spring 143.

I will now describe the magazine mechanism for automatically supplying unground tools to the holding and rotating means. 80 The magazine mechanism does not of itself constitute a part of the present invention, being set forth in my divisional application for magazine mechanism, Serial No. 198,057, filed October 23rd, 1917. 85

Secured to the main casting of the headstock is a bracket 144. This is held by bolts 145 extending through slotted holes in the bracket. These slotted holes permit limited adjustment of the bracket longitudinally of 90 the headstock, and after adjustment the bolts serve to secure the bracket in adjusted position. Secured to the tailstock is a bracket 146. This is held by bolts 147 extending through slotted holes in the bracket. These 95 slotted holes permit limited adjustment of the bracket longitudinally of the tailstock, and after adjustment the bolts serve to secure the bracket in adjusted position. The two brackets 144 and 146 are provided respectively at 148 and 149 with bearings in alinement with each other.

Pivoted upon the bracket 144 by means of a pivot pin at 150 extending into the bearing 148 is a magazine frame 105 plate 151. Pivoted upon the bracket 146 by means of a pivot pin at 152 extending into the bearing 149 is a magazine frame plate 153. The two plates 151 and 153 are similar to each other except that 110 they are oppositely formed, and the mechanisms carried by the plates are similar except that they are oppositely formed. A detailed description of but one of the plates and of the mechanism carried thereby will 115 be sufficient, the plate 151 and the corresponding mechanism being shown in detail in Figs. 14 and 15. Secured to the plate 151 are two relatively long guide bars 154 and 155 which taken together form one of the 120 body parts of the magazine. These bars are preferably angle-shaped in cross section, having flanges which project outward and having webs which are connected to the plate 151. Preferably, as shown, the bars 125 are adjustable with respect to the plate, each bar having two vertical guide tongues 156 and 157 which are slidably in vertical guide ways formed in the plate. The web of each angle bar is provided with slotted apertures 130

158 parallel to the guide tongues 156 and 157, and screws 159 extending through these apertures and entering the plate serve to lock the bars in adjusted positions. Preferably I provide means whereby the bars can be adjusted simultaneously and uniformly with respect to a fixed center line. As shown, the plate 151 has a recess 160 in which is pivotally mounted a lever 161, the pivot of the lever being at the aforesaid fixed center line. The lever is provided with two slots 162 and 163 positioned at equal distances from the pivot and receiving pins carried respectively by the bars 154 and 155. It will be seen that by loosening the screws 159 the two bars 154 and 155 can be moved equal distances in opposite directions by means of the lever 161, the bars being guided by the tongues 156 and 157. After adjustment the screws 159 are tightened, thus locking the bars in adjusted positions.

It will be understood as aforesaid, that the plate 153 is provided with mechanism similar to that already described. The two opposite sets of bars 154 and 155 serve as guides for the ends of the blanks to be ground, and by adjusting the bars in the way described the mechanism can be adapted for blanks of different diameters. In fact, by differently adjusting the devices on the two plates the mechanism can be adapted for blanks having different diameters at the two ends.

At the lower end of each bar 155 there is provided a lip 164 which serves to prevent the movement of the blanks by gravity out of the bottom of the magazine. By referring to Fig. 14 and observing the dot-and-dash lines thereof, it will be noted that the lip 164 is so positioned and that the guide tongues 156 and 157 are at such an angle, that as the bars 154 and 155 are separated or moved toward each other the lip 164 is moved downward or upward exactly to the extent necessary to maintain the axis of the lowermost blank in fixed position, notwithstanding differences in the size thereof. It will be understood that Fig. 14 shows the magazine with the lowermost blank in alignment with the centers 5 and 6. Fig. 15 shows the mechanism adjusted for very small blanks.

Each plate 151 and 153 is provided with a depending arm 165 having a slot 166 through which extends a horizontal rod 167. This rod 167 is carried by levers 168, 168 which are mounted upon a horizontal rock shaft 169. The rock shaft is mounted in bearings 170, 170 which are formed in brackets depending from the table 79.

Secured to the rock shaft 169 is an operating arm 171 provided at its end with a roller 172. Secured to the cam drum 113 is a cam plate 173 adapted to engage the roller 172 and swing the arm 171 downward. For

swinging the arm upward the aforesaid cam plate 173 is provided with a cam surface at 174.

During normal grinding operation the magazine mechanism is positioned substantially as indicated by dotted lines in Fig. 15. The position shown by full lines in Fig. 15 and also shown in the other figures of the drawing is the position which it occupies when supplying a fresh blank to be ground. With the grinding mechanism in its normal position the roller 172 is in its uppermost position. When a blank has been ground and has been discharged the roller 172 is engaged by the cam plate 173 and is forced downward, thus serving by means of the rock shaft 169, the rod 167 and the other parts described, to swing the magazine mechanism forward to the position shown in full lines in the drawings. In this position the lowermost blank in the magazine is in exact alignment with the centers 5 and 6 and the center 6 is moved toward the left in the way already described, thus moving the lowermost blank toward the left and into engagement with the center 5. When the blank has been thus engaged by the centers the continued movement of the cam drum brings the cam surface 174 into engagement with the roller 172 whereupon the roller is moved upward, thus restoring the magazine mechanism to the normal position shown by dotted lines in Fig. 15. As the magazine is moved backward the lowermost blank which has been engaged by the centers is drawn out and the other blanks slide downward to bring another blank into position to be engaged upon the next movement of the magazine.

It will be observed that the two main cams are so correlated that they do not interfere with each other. The vibratory motion resulting from the cam plates 75 and 76 begins after the several cam plates on the drum 113 have disengaged their respective rollers; and the vibratory motion ceases when the said cam plates again engage their respective rollers. It will furthermore be observed that the axis of the pivot 81 for the cable 79 is in the same transverse vertical plane as the axis of the cam drum 113. It is therefore possible to adjust the table 79 about the axis 81 without materially changing the positions of the several rollers with respect to the cam drum and the cam plates carried thereby.

What I claim is:

1. In a grinding machine, the combination of a grinding wheel, means for holding and turning the tool to be ground, a magazine for unground tools, automatic mechanism for successively supplying an unground tool from the magazine to the holding means, for moving the wheel toward the axis of the holding means into grinding position.

sition and for moving the wheel away from the axis of the holding means out of grinding position, and driving means for causing the said mechanism to move slowly during 5 grinding and rapidly at all other times.

2. In a grinding machine, the combination of a grinding wheel, means for holding and turning the tool to be ground, a magazine for unground tools, automatic mechanism

- 10 for successively supplying an unground tool from the magazine to the holding means, for moving the wheel toward the axis of the holding means into grinding position and for moving the wheel away from the axis of 15 the holding means out of grinding position, driving means for causing the said mechanism to move slowly during grinding and rapidly at all other times, and means for varying the said slow movement of the driving means without changing the rapid movement thereof.

3. In a grinding machine, the combination of means for holding a tool, a grinding wheel, a magazine for unground tools, and 25 mechanism for successively moving the wheel and the magazine toward and from the axis of the holding means, the magazine at each movement supplying a tool to the holding means and the grinding wheel at 30 each movement grinding a tool so supplied.

4. In a grinding machine, the combination of means for holding a tool, a grinding wheel, a magazine for unground tools, mechanism for successively moving the wheel and 35 the magazine toward and from the axis of the holding means, the magazine at each movement supplying a tool to the holding means and the grinding wheel at each movement grinding a tool so supplied, and means 40 for causing the holding means to engage an unground tool at each forward movement of the magazine and to release the ground tool at each backward movement of the wheel.

45 5. In a grinding machine, the combination of means for holding a tool, a grinding wheel, a magazine for unground tools, automatic mechanism for successively moving the wheel and the magazine toward and from 50 the axis of the holding means, the magazine at each movement supplying a tool to the holding means and the grinding wheel at each movement serving to grind a tool so supplied, and driving means for causing the 55 said mechanism to move slowly during grinding and rapidly at all other times.

6. In a grinding machine, the combination of means for holding a tool, a grinding wheel, a magazine for unground tools, automatic mechanism for successively moving the wheel and the magazine toward and from the axis of the holding means, the magazine at each movement supplying a 60 tool to the holding means and the grinding wheel at each movement serving to grind

a tool so supplied, driving means for causing the said mechanism to move slowly during grinding and rapidly at all other times, and means for varying the said slow movement of the driving means without 70 changing the rapid movement thereof.

7. In a grinding machine, the combination of means for holding a tool, a grinding wheel, a magazine for unground tools, automatic mechanism for successively moving 75 the wheel and the magazine toward and from the axis of the holding means, the magazine at each movement supplying a tool to the holding means and the grinding wheel at each movement grinding a tool so 80 supplied, mechanism for causing the holding means to engage an unground tool at each forward movement of the magazine and to release the ground tool at each backward movement of the wheel, and driving 85 means for the said mechanism arranged to operate slowly during grinding and rapidly at all other times.

8. In a grinding machine, the combination of means for holding a tool, a broad-faced grinding wheel adapted to engage the tool along the entire length of the part to be ground, a magazine for unground tools, mechanism acting automatically upon the completion of grinding of a tool to discharge 90 the tool and to supply an unground tool from the magazine to the holding means, and means operable during grinding and inoperable during the discharging and supplying of tools for vibrating the holding 100 means parallelly with the face of the wheel.

9. In a grinding machine, the combination of a movable table, means on the table for holding a tool, a grinding wheel adapted to engage the tool, a magazine on the table 105 for holding unground tools, a rotatable cam mounted independently of the table, and actuating mechanism on the table operated by the cam and acting automatically upon the completion of grinding of a tool to discharge 110 the tool and to supply an unground tool from the magazine to the holding means.

10. In a grinding machine, the combination of a movable table, means on the table for holding a tool, a broad-faced grinding 115 wheel adapted to engage the tool along the entire length of the part to be ground, a magazine on the table for holding unground tools, a rotatable cam mounted independently of the table, actuating mechanism on 120 the table operated by the cam and acting automatically upon the completion of grinding of a tool to discharge the tool and to supply an unground tool from the magazine to the holding means, and means operable 125 during grinding for vibrating the table parallelly with the face of the wheel, the said means being inoperative when the actuating mechanism is being operated by the cam.

11. In a grinding machine, the combina- 130

- tion of a movable table, means on the table for holding a tool, a broad-faced grinding wheel adapted to engage the tool along the entire length of the part to be ground, a magazine on the table for holding unground tools, actuating mechanism on the table adapted to discharge a ground tool from the holding means and to supply an unground tool from the magazine to the holding means, and two synchronously rotatable cams acting alternately in succession, one to operate the said actuating mechanism and the other to vibrate the holding means parallelly with the face of the wheel.
15. 12. In a grinding machine, the combination of an angularly adjustable table, means on the table for holding a tool, a grinding wheel adapted to engage the tool, a magazine on the table for holding unground tools, and actuating mechanism on the table acting automatically upon the completion of grinding of a tool to discharge the tool and to supply an unground tool from the magazine to the holding means.
20. 13. In a grinding machine, the combination of a table horizontally adjustable angularly, means on the table for holding a tool, a grinding wheel adapted to engage the tool, a magazine on the table for holding unground tools, a vertical rotatable cam mounted independently of the table, and actuating mechanism on the table operated by the cam and acting automatically upon the completion of grinding of a tool to discharge the tool and to supply an unground tool from the magazine to the holding means, the cam being so positioned with respect to the axis of table adjustment as to permit such adjustment without disturbing the relationship between the cam and the actuating mechanism.
25. 14. In a grinding machine, the combination of a movable slide, a table horizontally adjustable angularly on the slide, means on the table for holding a tool, a broad-faced grinding wheel adapted to engage the tool along the entire length of the part to be ground, a magazine on the table for holding unground tools, a vertical rotatable cam mounted independently of the table, actuating mechanism on the table operated by the cam and acting automatically upon the completion of grinding of a tool to discharge the tool and to supply an unground tool from the magazine to the holding means, the cam being so positioned with respect to the axis of table adjustment as to permit such adjustment without disturbing
30. the relationship between the cam and the actuating mechanism, and means operable during grinding for vibrating the slide parallelly with the face of the wheel, the said means being inoperative when the actuating mechanism is being operated by the cam.
35. 15. In a grinding machine, the combination of a grinding wheel, a headstock and a tailstock each provided with a center adapted to engage a tool to be ground, a magazine for unground tools comprising two sections mounted respectively on the headstock and the tailstock, and means for moving the magazine to cause it to supply an unground tool to the centers.
40. 16. In a grinding machine, the combination of a grinding wheel, a headstock and a tailstock each provided with a center adapted to engage a tool to be ground, a magazine for unground tools comprising two sections mounted respectively on the headstock and the tailstock and longitudinally adjustable relatively thereto, and means for moving the magazine to cause it to supply an unground tool to the centers.
45. 17. In a grinding machine, the combination of a grinding wheel, a headstock and a tailstock adjustable toward or away from each other and each provided with a center adapted to engage a tool to be ground, a magazine for unground tools comprising two sections mounted respectively on the headstock and the tailstock and adjustable therewith whereby the length of the magazine is changed as the distance between centers is changed, and means for moving the magazine to cause it to supply an unground tool to the centers.
50. 18. In a grinding machine, the combination of a grinding wheel, means adapted to hold a tool to be ground, a magazine for unground tools having two sections each comprising two parallel bars and a lip carried by the lower end of one bar, means for moving the magazine to a forward position to carry the lowermost tool engaged by the lip into alignment with the holding means, and means for adjusting the bars of each section toward or from each other and at the same time moving them longitudinally, whereby the magazine may be changed to accommodate tools of different sizes without moving the center of the lowermost tool out of alignment with the holding means.
55. In testimony whereof, I hereto affix my signature.

FRIEDERICH MÜLLER.
